UNITED STATES PATENT OFFICE

2,491,782

APPARATUS FOR STRAIGHTENING STRIP MATERIAL

Howard H. Talbot, Pittsburgh, Pa., assignor to
United Engineering & Foundry Company, Pittsburgh, Pa., a corporation of Pennsylvania

Application July 26, 1948, Serial No. 40,703

10 Claims. (Cl. 153—54)

1

This invention relates to apparatus for processing strip material and in particular to apparatus adapted to be employed for leveling or straightening metal strip, sheet or the like passed therethrough for processing by cold working.

Strip processing apparatus for cold working metal sheet or strip, as now applied to the rolling mill industry, usually includes one or more backing roll units disposed across the leveling or straightening rolls, each unit being individually adjustable to obtain the desired contour of rolls across the sheet or strip upon which the straightening operation is to be performed. It is found that between or across the span of such backing roll units, however, deflection of the straightening rolls is considerable so as to make it impossible to obtain a uniform working of the metal across the width thereof.

In order to overcome the objectionable features of strip processing apparatus now in use and to provide for a more uniformly leveled product, the apparatus herein disclosed embodies a plurality of backing or supporting rolls mounted upon an adjustable platen of sufficient flexibility to permit control of the roll contour thereof but having a rigidity which is adequate to offer desirable resistance to deflection of the rolls intermediate the adjustable supports. Once the adjustment of the platen has been accomplished and the deflection of the rolls established, any further adjustment thereof necessarily affects the contour of the straightening roll throughout its length by reason of the disturbance of the previously established deflections. It is possible, however, by coordinated adjustments of the supporting or backing-up rolls, across the width thereof, to obtain practically any desired contour, thus permitting allocation of heavy or light work or deep or shallow crimp across the sheet according to the requirements determined by the condition of the sheet or strip in the unprocessed state. Inasmuch as floating type bearings for supporting the straightening rolls of the apparatus are provided herein, no substantial loads will be imposed upon the bearing ends of the rolls during the processing operation. Then, too, by virtue of the adjustable upper roll supporting frame disclosed herein, it is possible to vary the angle at which the strip or sheet enters the apparatus and thus to provide for proper working of the metal as well as positive engagement thereof by the straightening rolls. Since a positive gripping of the strip is assured, the possibility of roll slippage usually resulting in the formation of "entry marks" on the strip is eliminated.

2

With the foregoing in mind, one of the objects of this invention is to provide a strip or sheet processing apparatus with which any desired contour transversely thereof can be obtained depending upon the condition of the unprocessed material and the results to be effected thereon.

Another object of this invention is to provide strip or sheet processing apparatus the straightening rolls of which are so supported by floating bearings at the ends thereof as to avoid the imposition upon the roll ends of any substantial loads incident to the strip processing operation regardless as to whether the operation involves a deep or a shallow crimp across the sheet.

Still another object of this invention is to provide a strip or sheet processing apparatus having a plurality of straightening rolls with the supporting or backing-up rolls thereof so arranged as to lend themselves to ready adjustment for controllably deforming the straightening rolls in order that the desired path upon which the unprocessed strip is to be projected may be quickly defined.

A further object of this invention is to provide a strip or sheet processing apparatus having a platen extending across the straightening rolls thereof and upon which the straightening roll backing members are supported, possessing sufficient flexibility to permit roll contour control but embodying a rigidity which offers desirable resistance to roll deflection intermediate the adjustable supports.

Still a further object of this invention is to provide a strip or sheet straightening apparatus having a plurality of supporting members extending longitudinally of the apparatus adapted simultaneously to be adjusted for imparting an equal controlled deflection to corresponding portions of each of the straightening rolls.

These objects, as well as the various other novel features and advantages of this invention, will become apparent from a reading of the following description and accompanying drawings of which:

Figure 1 is a plan view in section of the preferred embodiment of my invention taken on line I—I of Figure 2;

Figure 2 is an end elevation view partly in section taken on line II—II of Figure 1;

Figure 3 is a side elevation view taken on line III—III of Figure 1;

Figure 4 is a plan view of apparatus embodying my invention in modified form taken on line IV—IV of Figure 5;

Figure 5 is a sectional end view taken on line V—V of Figure 4, and

Figure 6 is a side elevation sectional view taken on line VI—VI of Figure 4.

With reference to the drawings, Figures 1 to 3, in which is illustrated the preferred embodiment of the invention herein disclosed, the strip metal straightening apparatus includes a lower frame 11, upon which is positioned an upper frame 12 adapted to be adjusted vertically from either of the two ends thereof by means of threaded spindles 13, engaging with spherical nuts 13a of the lower frame, upon which are mounted worm wheels 14 meshing with worms 15 keyed to shafts 16 which, extending transversely across the upper frame, are mounted in bearings 17 and rotated by hand wheels 18 secured thereto. Between the two frames and encircling each of the spindles 13 there are compression springs 20 which constantly urge apart the two frames.

Within the lower frame 11 there is a plurality of backing rolls 19 mounted in staggered relationship on separate short shafts 21 supported within in bearings provided in yokes 22 secured within and extending longitudinally of the frame. In contact with and mounted in suitable floating bearing-blocks 23 is a plurality of straightening rolls 24 adapted to engage the under side of a metal strip S as it passes through the straightening apparatus. The floating bearing-blocks 23 are slidably positioned within recesses 25 of the frame 11 and maintained therein by means of keeper plates 26 secured to the frame. Within the upper frame 12 there is positioned a plurality of straightening rolls 27, the shaft ends of which are rotatably secured within adequate bearings provided in floating bearing-blocks 28 urged vertically upward by means of springs 29 surrounding bolts 31 attached to the ends of the plates 28. Since the sets of straightening rolls 24 and 27 are supported by the floating bearing-blocks 23 and 28 respectively, there are no direct bearing loads except for the negligible end thrust which may be imposed thereon by the rolls.

Above the straightening rolls 27 there are a number of supporting or backing-up rolls 32, arranged in staggered relationship and each rotatably secured to separate short shafts 33 mounted in inverted yokes 34 attached to a flexible floating platen 35. On the upper surface of the platen 35 is attached a plurality of wear strips 36 upon which are positioned pressure blocks 37 which are slidable thereon transversely of the platen. Each of the pressure blocks 37 is provided with a recess 38 within which is received one of the eccentrics 39 formed as an integral part of each of a plurality of adjustable eccentric shafts 41 extending in a longitudinal direction within the upper frame 12. At spaced intervals adjacent to each of the eccentrics and formed in downwardly extending reinforcing webs 42 of the upper frame 12 are bearings 43 for supporting the eccentric shafts 41. Each one of the shafts 41 is independently rotatable for turning the eccentrics thereof as a unit, so that an equal pressure will be applied to the pressure blocks associated therewith lengthwise of the frame thereby controllably to deform the platen 35, and thus to cause corresponding backing-rolls to bear against and deflect equally all of the straightening rolls at the same corresponding points.

Each of the eccentric shafts 41 is independently rotatable, so that the pressures applied to the different sets of pressure blocks may be varied thus to provide for any desired straightening

roll contour. To one end of the first two shafts 41 on one side of the frame 12 there are keyed worm wheels 44 and 45 which are driven by two worms 46 and 47 respectively meshing therewith. The worm 46 is mounted on a hollow shaft 48 to which is attached a hand wheel 49 and the worm 47 is mounted on a spindle 51, passing through the hollow shaft 48, to the outer end of which is secured a hand wheel 52. Suitable bearings 53 and 54 are provided at the side of the upper frame 12 for supporting the shaft and spindle. To the corresponding ends of the next two shafts 41 are keyed worm wheels 55 and 56 respectively. The driving elements are mounted below the wheels 55 and 56 in bearings 57 and 58 and consist of a hollow shaft 59 having attached thereto a hand wheel 61 and a worm 62 in mesh with the wheel 55, and a spindle 63, passing through the hollow shaft 59, to which is secured a hand wheel 64 and a worm 65 in mesh with the wheel 56. On the opposite side of the frame 12 and keyed to the next two eccentric shafts 41 there are two worm wheels 66 and 67 in mesh with and driven respectively by two worms 68 and 69. The two worms 68 and 69 are mounted the one upon a hollow shaft 71 and the other upon a spindle 72 which passes therethrough. The hollow shaft 71 and the spindle 72 are supported by suitable bearings 73 and 74 provided at the side of the frame 12 and are manually rotated by hand wheels 75 and 76 respectively. The last eccentric shaft 41 is provided with a worm wheel 77 in mesh with and driven by a worm 78 keyed to a shaft 79. The shaft 79 is mounted in bearings 81 and 82 on the side of the frame and has affixed to the end thereof a hand wheel 83.

On the drive side of the leveling apparatus, all of the straightening rolls are provided with shaft extensions to which is connected, by means of universal couplings or the like, separate driven shafts of a power operated driving gear unit.

One of the modified forms of the invention herein disclosed is illustrated in the drawings Figs. 4 to 6. In the modified form, the leveling apparatus includes a lower frame 101, an upper adjustable frame 102, a plurality of sheet or strip metal lower and upper straightening rolls 103 and 104 respectively and a plurality of lower and upper backing-up rolls 105 and 106 in contact therewith.

For tilting the upper frame 102 to any desired angle with respect to the lower frame 101, there are rotatably secured within the upper frame threaded spindles 109, engaging with spherical nuts 109a in the openings 111 at the four corners of the lower frame. The spindles 109 have keyed thereon worm wheels 112 which are in mesh with driving worms 113 keyed to shafts 114 extending transversely across the upper frame and supported in suitable bearings 115 and 116. The shafts 114 have secured to the operator's side thereof hand wheels 117 by which they are rotated for raising and lowering either end of the upper frame. Between the two frames and encircling the spindles 109 are compression springs 110 which constantly urge apart the two frames. Within the lower frame 101, the backing-up rolls 105 are rotatably supported upon short shafts 107 secured within yokes or channels 108 attached to and extending longitudinally of the frame. The straightening rolls 103 extend transversely of the lower frame and are mounted at their ends in suitable floating bearing-blocks

118 slidably maintained within recesses 119 in the sides of the frame by keeper plates 121.

The upper straightening rolls 104 are mounted in floating bearing-blocks 122 maintained within recesses 123 of the upper frame by keeper plates 124. The bearing-blocks 122 are urged vertically upwards by springs 125 surrounding bolts 126 attached to the ends of the blocks 122.

Above the straightening rolls 104 and in contact therewith are the upper backing-up rolls 106 which are mounted on short shafts 127 secured within inverted yokes or channels 128 affixed to a flexible platen 129. Two grooves 131 along the inner transversely opposite sides of the upper frame are provided for supporting the platen 129 at the edges thereof.

On the upper side of and affixed to the platen 129 there are three rows of brackets 132, each supporting a short shaft 133 having rotatably secured thereto a connecting rod 134. The upper end of each connecting rod 134 is mounted on a separate eccentric 135 provided on each of a plurality of eccentric shafts 136. The eccentric shafts are supported at a plurality of points along their lengths in suitable bearings 137 mounted in transverse reinforcing ribs 138 of the upper frame.

The first two eccentric shafts have keyed to one end thereof worm wheels 139 and 141 in mesh with and driven by two worms 142 and 143 respectively. The two worms 142 and 143 are, respectively, secured to a hollow shaft 144 and to a spindle 145 passing therethrough. The hollow shaft and spindle are supported in suitable bearings 146 and 147 at the side of the frame and are manually rotatable by hand wheels 148 and 149. The remaining eccentric shaft is provided with a worm wheel 151 with which a driving worm 152 engages. A shaft 153, to which the worm 152 is secured passes beneath and in line with the hollow shaft 144 and the spindle 145, is mounted on the frame in suitable bearings 154 and 155, and is manually rotated by means of a hand wheel 156 affixed thereto.

As in the case of the preferred form of my invention, on the drive side of the leveling apparatus all of the straightening rolls are provided with shaft extensions to which are connected by means of universal couplings, or the like, separate driven shafts of a power operated driving gear unit.

In accordance with the provisions of the patent statutes, I have explained the principle and operation of my invention and have illustrated and described what I consider to represent the best embodiment thereof. However, I desire to have it understood that within the scope of the appended claims, the invention may be practiced otherwise than as specifically illustrated and described.

I claim:

1. Apparatus for cold working strip metal comprising an upper and a lower frame, a plurality of straightening rolls rotatably secured within each of said frames, supporting means interposed between one of said frames and said straightening rolls contained therein for preventing substantial deflection of said rolls, a flexible platen extending across the inner portion of the other of said frames, a plurality of groups of supporting means secured to the side of said platen adjacent the straightening rolls contained within said last mentioned frame, pressure applying means secured to the opposite side of said platen engaging with said last mentioned frame

for controllably deforming said platen across the width thereof thereby controlling the deflection of said last mentioned straightening rolls, and means for adjusting one of said frames vertically with respect to the other for varying the entry angle between said two sets of straightening rolls.

2. Apparatus for cold working strip metal comprising an upper and a lower frame, a plurality of straightening rolls rotatably secured within each of said frames, supporting rolls interposed between one of said frames and said straightening rolls contained therein for preventing substantial deflection of said straightening rolls, a flexible platen extending across the inner portion of the other of said frames, a plurality of groups of supporting rolls secured to the side of said platen adjacent the straightening rolls contained within said last mentioned frame, pressure applying means secured to the opposite side of said platen engaging with said last mentioned frame for controllably deforming said platen across the width thereof thereby controlling the deflection of said last mentioned straightening rolls, and means for adjusting one of said frames vertically with respect to the other for varying the entry angle between said two sets of straightening rolls.

3. Apparatus for cold working strip metal comprising an upper and a lower frame, a plurality of straightening rolls rotatably secured within each of said frames, a plurality of rolls, secured within one of said frames, interposed between said straightening rolls and said frame for preventing substantial deflection of said straightening rolls, a flexible platen extending across the inner portion of the other of said frames, a plurality of groups of rolls secured to the side of said platen adjacent to and for supporting said straightening rolls contained within said last mentioned frame, pressure applying means secured to the opposite side of said platen and engaging with said last mentioned frame for controllably deforming said platen across the width thereof thereby controlling the deflection of said last mentioned straightening rolls, and means for adjusting one of said frames vertically with respect to the other for varying the entry angle between said two sets of straightening rolls.

4. Apparatus for cold working strip metal comprising an upper and a lower frame, a plurality of straightening rolls rotatably secured within each of said frames, a plurality of rolls, secured within one of said frames, interposed between said straightening rolls and said frame in which they are contained, for preventing substantial deflection of said straightening rolls, a flexible platen extending across the inner portion of the other of said frames, a plurality of groups of rolls secured to the side of said platen adjacent to and for supporting said straightening rolls contained within said last mentioned frame, a plurality of shafts extending longitudinally of and rotatably secured within said last mentioned frame, a plurality of eccentrics secured to each of said shafts, separate links engaging at one end with said eccentrics on each of said shafts and loosely pinned at the opposite ends thereof to said platen and separate means for rotating each of said shafts controllably to deform said platen across the width thereof thereby controlling the deflection of said last mentioned straightening rolls.

5. Apparatus for cold working strip metal comprising an upper and a lower frame, a plurality of straightening rolls rotatably secured within each of said frames, a plurality of rolls, secured

within one of said frames, interposed between said straightening rolls and said frame in which they are contained for preventing substantial deflection of said straightening rolls, a flexible platen extending across the inner portion of the other of said frames, a plurality of groups of rolls secured to the side of said platen adjacent to and for supporting said straightening rolls contained within said last mentioned frame, a plurality of rows of shafts extending longitudinally of and rotatably secured within said last mentioned frame, a plurality of eccentrics secured to each of said shafts, separate links engaging at one end with said eccentrics of each of said shafts and secured at the opposite ends thereof to said platen, separate means for rotating each of said shafts controllably to deform said platen across the width thereof thereby controlling the deflection of said last mentioned straightening rolls and means for adjusting one of said frames vertically with respect to the other for varying the entry angle between said two sets of straightening rolls.

6. Apparatus for cold working strip metal comprising an upper and a lower frame, a plurality of straightening rolls rotatably secured within said lower frame, means interposed between said rolls and said frame for supporting said rolls across the width thereof, a plurality of straightening rolls yieldably supported at their ends within said upper frame, a flexible platen extending across said upper frame, a plurality of groups of supporting rolls rotatably secured to said platen for engagement with said last mentioned straightening rolls, a plurality of groups of pressure applying means secured to said frame and to the upper portion of said platen, separate means for adjusting each of said groups of pressure applying means to deform said platen in varying degrees across the width thereof for controlling the contour of said straightening rolls, and means for adjusting said upper frame in a vertical direction with respect to said lower frame for varying the entry angle between said two sets of straightening rolls.

7. Apparatus for cold working strip metal comprising an upper and a lower frame, a plurality of straightening rolls rotatably secured within said lower frame, means interposed between said rolls and said frame for supporting said rolls across the width thereof, a plurality of straightening rolls yieldably supported at their ends within said upper frame, a flexible platen extending across and secured at the edges thereof to said upper frame, a plurality of groups of supporting rolls rotatably secured to said platen for engagement with said last mentioned straightening rolls, a plurality of groups of pressure applying means secured to said frame and to the upper portion of said platen, separate means for adjusting each of said groups of pressure applying means to deform said platen in varying degrees across the width thereof for controlling the contour of said straightening rolls, and means for adjusting said upper frame in a vertical direction with respect to said lower frame for varying the entry angle between said two sets of straightening rolls.

8. Apparatus for cold working strip metal comprising an upper and a lower frame, a plurality of straightening rolls rotatably secured within said lower frame, means interposed between said rolls and said frame for supporting said rolls across the width thereof, a plurality of straightening rolls yieldably supported at their ends within said upper frame, a flexible platen extending across the inner portion of said upper frame, a plurality of groups of supporting rolls rotatably secured to said platen for engagement with said last mentioned straightening rolls, pressure applying means secured to said upper frame and to the upper portion of said platen for deforming said platen across the width thereof to control the contour of said straightening rolls, and means for adjusting said upper frame in a vertical direction with respect to said lower frame for varying the entry angle between said two sets of straightening rolls.

9. Apparatus for cold working strip metal comprising an upper and a lower frame, a plurality of straightening rolls rotatably secured within each of said frames, supporting means for said straightening rolls, said supporting means in at least one of said frames comprising a flexible platen extending across the inner portion thereof, backing-up rolls secured to the side of said platen adjacent the straightening rolls, and pressure applying means secured to the opposite side of said platen engaging with the frame in which said platen is contained for controllably deforming said platen thereby controlling the deflection of said straightening rolls.

10. Apparatus for cold working strip metal comprising an upper and a lower frame, a plurality of straightening rolls rotatably secured within each of said frames, supporting means for said straightening rolls, said supporting means in at least one of said frames comprising a flexible platen extending across the inner portion thereof, backing-up rolls secured to the side of said platen adjacent the straightening rolls, and pressure applying means secured to the opposite side of said platen engaging with the frame in which said platen is contained for controllably deforming said platen thereby controlling the deflection of said straightening rolls, and means for adjusting one of said frames vertically with respect to the other for varying the entry angle between said two sets of straightening rolls.
